Primary Examiner — Robert M Spear*Assistant Examiner* — Marissa J Cash(57) **CLAIM**

The ornamental design for a trocar, as shown and described.

DESCRIPTION

FIG. 1 is a perspective view of a first design embodiment of a trocar of the present application;

FIG. 2 is a front view of a first design embodiment of a trocar of the present application;

FIG. 3 is a right side view of a first design embodiment of a trocar of the present application;

FIG. 4 is a top view of a first design embodiment of a trocar of the present application;

FIG. 5 is an exploded view of a first design embodiment of a trocar of the present application;

FIG. 6 is a perspective view of a second design embodiment of a trocar of the present application;

FIG. 7 is a front view of a second design embodiment of a trocar of the present application;

FIG. 8 is a right side view of a second design embodiment of a trocar of the present application;

FIG. 9 is a top view of a second design embodiment of a trocar of the present application; and,

FIG. 10 is an exploded view of a second design embodiment of a trocar of the present application.

The embodiments described herein are provided by way of explanation of the invention.
